his attorney.

UNITED STATES PATENT OFFICE

FRANK C. LA MAR, OF NEW YORK, N. Y., ASSIGNOR TO GREAT WESTERN FUSE COMPANY, OF PITTSBURGH, PENNSYLVANIA, A CORPORATION OF DELAWARE

RENEWABLE FUSE

Application filed March 23, 1928. Serial No. 264,139.

The object which I have in view is the provision of a new and improved renewable fuse of substantial yet inexpensive construction, which may be readily assembled and disassembled by unskilled persons and without the use of special tools, and which will be sealed against the escape of flame from the fuse body along the terminal blades.

In the accompanying drawings, wherein I have illustrated the best embodiment of the principles of my invention now known to me, Fig. 1 is a longitudinal section of the fuse.

Fig. 2 is an end view of the same, looking from the left in Fig. 1 and with the screw cap omitted.

Fig. 3 is a plan view of the sealing disk.

Fig. 4 is an outer face view of the slotted washer.

Fig. 5 is an inner face view of the same.

Fig. 6 is a side elevation of one of the terminal blades, the left one in Fig. 1.

Fig. 7 is an inner end view of the same.

Fig. 8 is an end view of one of the ferrules.

Referring to the drawings, 1 represents the tubular shell of the fuse made of suitable insulating material, such as fibre.

On each end of the shell 1 a metal ferrule 2 is fixed, as by threaded engagement and riveting.

The outer ends of the ferrules are provided with recesses which form the seats 3. I prefer to provide two of such seats in each ferrule and dispose them diametrically of the ferrule as shown in Fig. 8.

The shell and the ferrules comprise the tubular body of the fuse.

4 and 5 indicate the two metal terminal blades whose inner ends are reduced and have detachably connected thereto the ends of the fusible link 6.

One of said terminal blades, the right hand one 4 in Fig. 1, has fixedly mounted thereon the circular closure head 7 which bears against the end of the corresponding ferrule 2 and is provided on its inner face with a diametrically disposed rib 8 whose ends engage the seats 3 and thus prevent relative rotation between the closure head and the body of the fuse.

An annular cap 9 screws on the end of the ferrule and clamps the head 7 snugly in place on the ferrule.

The other blade 5 is provided with a laterally extending abutment 10 extending on either side thereof and adjacent to the outer side of said abutment with two opposed notches 11 in its side edges which form a restricted neck in the blade.

When the parts are assembled the abutment 10 lies slightly within the outer end of the corresponding ferrule 2.

12 indicates a slotted washer which is slipped down over the blade 5 against the end of the ferrule and is provided with a portion of less diameter having arcuate walls 13 which fit into the end of the ferrule. The slotted washer bears against the abutment 10.

At either side the slotted washer is provided on its under side with a lug 14 which engages the corresponding seat 3 in the end of the ferrule to prevent relative rotation between the washer and the body of the fuse.

15 indicates a sealing disk which is cut away inwardly from one side to form a rectangular aperture 16 of sufficient width to span the neck of the blade 5 between the notches 11.

After the slotted washer has been placed in position, the sealing disk is slid across the face of the washer with the side edges of its aperture 16 engaging under the outer shoulders or walls of the notches 11 in the blade and the inner face of the disk bearing on the washer.

Thus the ends of the slot in the washer 12 are sealed from without by the disk 15 while the sides of the slot are sealed from within by the abutment 10 of the blade.

The disk is circular and of substantially the same diameter as the washer, so that when the disk is in its sealing position the perimetral edges of the washer and disk are in substantial registration.

The washer is provided with a fixed filler block 17 on its outer face on the opposite side of the blade from the side from which the sealing disk is slid into position, which block 100

the legs of the disk straddle. The block also acts as a guide for the sealing disk.

After the washer and disk are in position the annular cap 18 is screwed onto the end of the ferrule clamping down the sealing disk and the filler block and thus holding the parts fixedly to the body of the fuse.

In assembling the fuse, the terminal blades are attached to the ends of the fusible link 10 and the terminal blade 5 and the link are inserted through the right end of the body in Fig. 1 until the closure head 7 seats on the end of the body. The corresponding cap 9 is then screwed in place.

15 The slotted washer is then slipped down over the blade 5 against the abutment 10 and engaging the seats 3 in the ferrule. The sealing disk is then slipped into position and the corresponding cap 9 is then screwed onto 20 the end of the body.

When the parts are to be disassembled, the right hand screw cap, in Fig. 1, is first removed and then the left hand cap and the sealing disk and slotted washer. The terminals are thus released.

It is evident that the assemblage and disassembly of my improved fuse may be quickly and conveniently accomplished.

It is further evident that the slot of the washer is sealed at its sides by the abutment on the blade and at its ends by the sealing disk. Thus the passage of flames outwardly along the blade is prevented.

The fuse is simple, contains few parts and is therefore inexpensive to manufacture.

What I desire to claim is:—

1. In a renewable fuse, the combination of a tubular body, a terminal blade arranged to extend through the end of the body and provided with a lateral abutment and with shoulders adjacent the outer side of said abutment, a slotted washer arranged to be slipped down over the end of the blade and rest on said abutment and the end of the body, said washer and body having interengaging portions which prevent relative rotation between the parts, a sealing disk having an open aperture with parallel sides forming a pair of legs and arranged to be slid over the face of the washer, the legs of said disk straddling the blade and engaging the shouldered portions thereof to hold the washer against the abutment, portions of the disk and the washer interengaging to prevent relative rotation of the disk and washer, and an annular cap screwed onto the end of the body and having an inwardly extending flange which engages the sealing disk and clamps it and the washer fixedly to the body.

2. In a renewable fuse, the combination of a tubular body, a terminal blade arranged to extend through the end of the body and provided with a lateral abutment and with shoulders adjacent the outer side of said

abutment, a slotted washer arranged to be slipped down over the end of the blade and rest on said abutment and the end of the body, said washer and body having interengaging portions which prevent relative rotation between the parts, a one-piece sealing disk having a central open aperture and arranged to be slid over the face of said washer and to straddle the blade and engage the shouldered portions of said blade to hold said washer against said abutment, an annular cap screwed onto the end of the body and clamping the sealing disk and washer fixedly thereto, and the washer being provided with a filler block which is straddled by the sealing disk and engaged thereby to prevent relative movement between the disk and the washer.

Signed at New York, N. Y., this 19th day of March, 1928.

FRANK C. LA MAR.
